UNITED STATES PATENT OFFICE.

FRED SANDERS, OF LOS ANGELES, CALIFORNIA.

INTERCHANGEABLE CLIPPER AND VIBRATOR.

Application filed October 12, 1927. Serial No. 225,609.

This invention relates to improvements in mechanically operated clippers and vibrators.

The general object of this invention is to provide a power operated tonsorial device including means for including interchangeable hair clipping and massage means.

Another object of my invention is to provide a device of the class described having a handle portion adapted to be held in the operator's hand in which is encased an electric motor for actuating the attachment.

A further object of the invention is to provide an improved massage device having both rotatable and reciprocal movement.

Other objects of this invention will be apparent from the following description taken in connection with the accompanying drawings wherein:—

Fig. 1 is a top plane view partly in section of my device showing the clipper attachment in an operative position.

Fig. 2 is a side view of the clipper attachment detached from the operating device.

Fig. 3 is a side view partly in section of my device showing the massage attachment in an operative position.

Fig. 4 is a section taken on line 4—4 of Fig. 3 and

Fig. 5 is an enlarged section taken on line 5—5 of Fig. 1.

Referring to the drawings by reference characters I have indicated my improved clipper and massage device generally at 10.

This device as shown in the accompanying drawing comprises a handle portion 11 having a clipper attachment 12 (see Fig. 1) and a massage attachment 14 (see Fig. 3). The handle 11 is shown as comprising a body portion 15 having a closure 16 at one end and a cap 17 at the opposite end. The closure 16 and a cap 17 may be secured to the body in any suitable manner as by screws 18 and 19.

The handle 11 is preferably of a somewhat elliptical shape shown in the drawings so as to be conveniently held in an operator's hand. An electric motor 20 is positioned in the handle 11 and may be secured thereto by screws 21 as shown or in any other suitable manner. The motor 20 is preferably made in a shape to conform to the shape of the handle 11 but may be of any approved type.

As shown in the drawing electric current is furnished to the motor by a cable 22 which passes through the closure 16 and connects to an electric push switch 23. The switch 23 includes a push button 24 and may be of any

desired type wherein pressure must be maintained on the push button to make electric contact through the switch.

For maintaining pressure upon the switch 23 push button 24 while the device is being operated I provide a lever 25 pivoted to the body portion 15 as at 26. For normally urging the lever 25 away from the handle I provide a coiled spring 27 and for limiting the outward movement of the lever I provide a cross bar as shown at 28 in Figs. 1 and 3.

The cap 17 includes a reduced end portion 30, has an aperture 31 therethrough and terminates in a reduced externally screw threaded tip 32.

Each of the attachments 12 and 14 includes a shank 34 which is apertured for the reception of a sleeve 35 in which an operating shaft 36 is mounted. The sleeve 35 is preferably secured to the shank 34 by pins 37, as shown, or in any other suitable manner. A nut 38 is positioned on the sleeve 35 and includes internal screw threads to match the screw threads on the tip 32 of the cap 17. This nut 38 is freely rotatable on the sleeve 35. A collar 39 secured to the sleeve in any desired manner prevents longitudinal movement of the nut along the sleeve.

The exposed end of the operating shaft 36 is provided with a plurality of splines as shown at 40 which are adapted to be positioned in corresponding grooves 41 in the end of the armature shaft 42 of the motor 20.

To operatively position either the clipper attachment 12 or the massage attachment 14 to the handle 11 it is only necessary to insert the sleeve 35 in the aperture 31 of the reduced end 30 of the cap and screw the nut 38 on the screw threaded tip 32.

When the sleeve 35 is placed in the aperture 31 the splines 40 on the end of the shaft 36 will be positioned in the grooves 41 of the armature shaft and when the motor 20 is operated the armature shaft will rotate the shaft 36 to actuate the attachment.

The particular construction of the clipper actuating mechanism other than what has previously been set forth such as the sleeve 35, shaft 36 and nut 38 may be of any desired construction.

The massage device 14 includes besides the shank 34 a body portion 45 having recesses 46 and 47 therein. The shaft 36 extends into the recess 46 and is provided with a bevel gear 48 which meshes with another bevel gear 49 on a shaft 50 supported in the housing 45.

The shaft 50 is positioned in a recess 51 in another shaft 52 which is positioned in the recess 47. The shaft 52 is slideable on the shaft 50 and is adapt'd to be driven by the shaft 50 through the medium of a key 53. The shaft 52 is adapted to be retained in position in the aperture 47 by a set screw 54 which includes a reduced end 55 which is positioned in an endless spiral groove 56 in the shaft 52. Thus it will be seen that when the shaft 50 revolves the shaft 52 the shaft 52 will also be caused to reciprocate along the shaft 50.

To the protruding end of the shaft 52 I have shown a massage device indicated generally by 58. The massage device shown includes a rubber vacuum cup 59 secured to a hub 60 which is provided with a recess 61 for the reception of the end of the shaft 52. The hub 60 is shown as attached to the shaft 52 by a bayonet joint 62 of which a pin 63 is secured to the shaft 52 and a slot 64 is formed in the hub 60. If desirable I may provide a sufficiently strong flat spring 65 at the bottom of the recess 61 to maintain tension on the bayonet joint.

The housing 45 is provided adjacent its lower end with a counter bore 67 so that when the device is operated the hub 60 of the massage device will have clearance to reciprocate.

Any other suitable means of attaching the massage device 58 to the shaft may be employed or the massage device may be rigidly secured to the shaft, but by making it detachable various forms of massage devices may be quickly attached to the shaft.

What I claim is:

1. In a tonsorial implement, a hollow handle, a closure secured to one end of said handle, a cap secured to the opposite end of said handle, said cap including a reduced end portion and a threaded tip, an aperture extending through said end portion and said tip, an electric motor positioned in said handle and secured thereto, said motor including an armature shaft, a control switch for said motor, a work member having a shank, a threaded member on said work member and engaging said threaded tip and means to drive said work member from said armature shaft.

2. In a device of the class described, a hollow handle, said handle having an end portion including a reduced threaded tip, an aperture extending through said tip and a work member having a shank, an aperture in said shank, a sleeve in said aperture and extending beyond the end of said shank, said sleeve being fixed to said shank, a threaded nut positioned on said sleeve, a collar on said sleeve adapted to retain said nut adjacent the end of said shank, said nut being adapted to engage said threaded tip to removably secure said shank to said handle, a rotatable shaft positioned in said sleeve, said shaft having its end extending beyond the free end of said sleeve, the end of said

shaft being provided with splines, said sleeve when said nut is in engagement with said threaded tip being positioned in said aperture in said tip, a shaft in said handle, the end of said rotatable shaft being operatively connected to said handle shaft and means to drive said handle shaft.

3. In a device of the class described, a hollow handle including a cap, an aperture extending through the end portion of said cap, a drive shaft in said handle, a shank, an aperture in said shank, a sleeve in said aperture and extending beyond the end of said shank and said sleeve being rigidly fixed to said shank, a rotatable member on said sleeve, a collar on said sleeve adapted to retain said member adjacent the end of said shank, means on said member adapted to coact with the end of said cap to removably secure said shank to said handle, a rotatable shaft positioned in said sleeve, said shaft having its end extending beyond the free end of said sleeve, said sleeve when said shank is attached to said cap being positioned in said aperture in said cap, means to connect said drive shaft to said rotatable shaft whereupon when said drive shaft is rotated said first shaft will be rotated.

4. In a device of the class described, a handle, an electric motor in said handle including an armature shaft, a shank removably attached to said handle, a second shaft in said handle in engagement with said armature shaft, a body portion on said shank, a recess in said shank, a bevel gear secured to said second shaft and positioned in said recess, a third shaft supported by said body portion, a second bevel gear, said gear being secured to said third shaft and positioned in said recess and being in mesh with said first bevel gear, a second recess in said body portion, a fourth shaft positioned in second recess, an aperture in said fourth shaft, said third shaft being positioned in said aperture and keyed to said fourth shaft, said fourth shaft being mounted for reciprocation upon said third shaft, a spiral groove in said fourth shaft, a set screw in said body portion having a reduced end adapted to be positioned in said spiral groove whereupon when said fourth shaft is rotated it will be caused to reciprocate and means for attaching an implement to said fourth shaft.

5. In a device of the class described, a hollow handle, an electric motor positioned in said handle, said motor including an armature shaft, an electric control switch in said handle having an operating member extending out of said handle, a shank, an aperture in said shank, a sleeve in said aperture and extending beyond the end of said shank, said sleeve being rigidly fixed to said shank, a member on said sleeve, a collar on said sleeve adapted to retain said member adjacent the end of said shank, means on said member adapted to engage said handle to removably secure said shank to said handle and a rotatable shaft positioned in said

sleeve, said shaft having its end extending beyond the free end of said sleeve, the end of said shaft being provided with splines, said shaft when said member is in engagement with said handle being positioned in an aperture in the end of said armature shaft, said armature shaft aperture having grooves therein corresponding to said splines on said first shaft whereupon when said armature shaft is rotated said first shaft will be rotated.

6. In a device of the class described, a hollow handle, a closure secured to one end of said handle, a cap secured to the opposite end of said handle, said cap including a reduced externally threaded tip, an aperture extending through said end portion and said tip, an electric motor positioned in said handle and removably secured thereto, said motor including an armature shaft, an electric control switch in said handle and having an operating member on said handle, a shank, an aperture in said shank, a sleeve in said aperture and extending beyond the end of said shank, said sleeve being rigidly fixed to said shank, a recessed nut positioned on said sleeve, a collar on said sleeve adapted to retain said nut adjacent the end of said shank, said nut being adapted to engage said threaded tip to removably secure said shank to said handle, a rotatable shaft positioned in said sleeve, said shaft having its end extending beyond the free end of said sleeve, the end of said shaft being provided with splines, said sleeve when said nut is in engagement with said threaded tip being positioned in said aperture in said end portion of said cap and said splined end of said shaft being positioned in an aperture in the end of said armature shaft, said armature shaft aperture having grooves therein corresponding to said splines on said first shaft whereupon when said armature shaft is rotated said first shaft will be rotated.

7. In a device of the class described, a hollow handle, a closure removably secured to one end of said handle, a cap removably secured to the opposite end of said handle, said cap including a reduced end portion and a reduced externally threaded tip, an aperture extending through said end portion and said tip, an electric motor secured in said handle, said motor including an apertured armature shaft, an electric control switch in said handle and having an operating member extend-

ing out of said handle, a lever pivoted to said handle and overlaying said switch operating member adapted upon movement thereof to actuate said switch, resilient means adapted to normally urge said lever away from said handle, means for limiting said outward movement of said lever, a working member having a shank, an aperture in said shank, a sleeve in said aperture extending beyond the end of said shank, said sleeve being rigidly fixed to said shank, a recessed internally threaded nut positioned on said sleeve, a collar on said sleeve adapted to retain said nut adjacent the end of said shank, said nut being adapted to engage said externally threaded tip to removably secure said working member to said handle, a rotatable work shaft positioned in said sleeve, said work shaft having its end extending beyond the free end of said sleeve, the end of said shaft being provided with splines, said sleeve when said nut is in engagement with said threaded tip being positioned in said aperture in said end portion of said cap and said splined end of said shaft being positioned in the aperture in the end of said armature shaft, said armature shaft aperture having grooves therein corresponding to said splines on said work shaft whereupon when said armature shaft is rotated said work shaft will be rotated, a body portion on said shank, a recess in said shank, a bevel gear secured to said work shaft and positioned in said recess, a third shaft supported by said body portion, a second bevel gear, said gear being secured to said third shaft and positioned in said recess and being in mesh with said first bevel gear, a second recess in said body portion, a fourth shaft positioned in said second recess, an aperture in said fourth shaft said third shaft being positioned in said aperture and keyed to said fourth shaft, said fourth shaft being reciprocally mounted upon said third shaft and having a spiral groove in its surface, a set screw in said body portion having a reduced end adapted to be positioned in said spiral groove whereupon rotation of said fourth shaft will cause reciprocation thereof, and cause means on said fourth shaft for attaching thereto an implement to be rotated and reciprocated.

In testimony whereof, I hereunto affix my signature.

FRED SANDERS.
